George D. Wilson, Inventor
By W. W. Morris Attorneys,

C. A. Snow & Co.

UNITED STATES PATENT OFFICE.

GEORGE D. WILSON, OF POMEROY, WASHINGTON.

HORSE-POWER.

SPECIFICATION forming part of Letters Patent No. 633,978, dated September 26, 1899.

Application filed April 2, 1898. Serial No. 676,229. (No model.)

To all whom it may concern:

Be it known that I, GEORGE D. WILSON, a citizen of the United States, residing at Pomeroy, in the county of Garfield and State of Washington, have invented a new and useful Horse-Power, of which the following is a specification.

The present invention is designed chiefly to increase and prolong the life and period of usefulness of that class of motors known as "horse-powers," the principal features being to equalize the strain upon the vertical shafts, which are in mesh with the line-shafting, by means of which motion is transmitted to the machinery to be driven, thereby obviating a stripping of the cogs and an unequal strain of said vertical shaft in its bearings.

Other objects and advantages will appear in the course of the subjoined description, and in order that the details of the construction may be fully comprehended reference is to be had to the drawings hereto attached, in which corresponding parts are indicated by and referred to in the following description by the same reference characters.

For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof is shown in the accompanying drawings, in which—

Figure 1 is a top plan view of a horse-power, showing the application of the invention. Fig. 2 is a central longitudinal section thereof on the plane indicated by the dotted line 3 3 of Fig. 1. Fig. 3 is a detail view in perspective of a bearing for one of the idle or power-transmitting gear-wheels. Fig. 4 is a transverse section about on the line X-X of Fig. 1.

The bed of the horse-power consists of a frame composed of longitudinal and transverse bars firmly connected, forming a substantial structure. Transverse bars 1 are applied to the end portion of the bed or base 2 and are connected intermediate of their ends by means of a bridge-tree 3. A vertical shaft

4 is located about centrally of the base and receives the master-wheel 5, which is journaled upon the upper end thereof and which is internally toothed. The sweep (not shown) to which the horse or team is to be hitched is applied to the master-wheel in any of the usual ways, which are well understood in the art. The line of shafting 6, extending lengthwise of the base, is journaled in bearings applied to the cross-timbers thereof and is supplied with pinions 7, which intermesh with gear-wheels 8, applied to the lower ends of vertical shafts 9, located at the ends of the bridge-tree 3. These vertical shafts 9 are stepped in bearings applied to cross-timbers of the bed or base 2, and their upper ends are journaled in plates 10, secured to the terminals of the part 3. Pinions 11 are secured to the upper ends of the vertical shafts 9 and receive motion from the master-wheel through the intervention of idle or power-transmitting gear-wheels 12.

The pinions 11 are located at diametrically opposite points with reference to the master-wheel 5, and a pair of idle or power-transmitting gears 12 is provided for each pinion, the wheels constituting each pair of gear-wheels 12 being located upon opposite sides of the respective pinions 11 and intermeshing therewith and with the internally-toothed portion of the master-wheel. This disposition of the pairs of gear-wheels 12 equalizes the strain upon the pinions 11 and centralizes them between the contiguous portions of the gear-wheels 12 in mesh therewith, thereby preventing wearing and stripping of the cogs of the pinions and obviating the tendency to cant the vertical shafts 9 and cause them to wear unevenly in their bearings and to get out of plumb, which would be objectionable and cause the intermeshing gear elements 7 and 8 to bind and soon wear out, besides detracting materially from the effectiveness and power of the motor. It will also be observed that a greater number of teeth of the pinions 11 are brought into action, thereby enabling smaller pinions 11 being used, which is desirable in motors of this type.

Plates 13 are provided with stub-axles 14, upon which the gear-wheels 12 are mounted. These plates have adjustable connection with the transverse bars 1, so as to be moved to

secure the proper meshing of the cogs with the cogs of the master-wheel and the pinions 11. Slots 15 are formed obliquely in the corner portions of the plate 13 in such a manner as to admit of the gear-wheels 12 being moved so as to bring their teeth into meshing relation with the teeth of the master-wheel and the pinions 11 with a greater or less degree, as may be required. In this connection it is to be noted that if the plates 13 were moved laterally or in a direction at right angles to the line of the bridge-tree the gear-wheels 12 would be moved into engagement with the master-wheel and out of engagement with the pinion, or vice versa. On the other hand, if the plates 13 were moved in lines parallel with the bridge-tree an adjustment thereof with reference to the pinions 11 could not be secured. It is essential, therefore, that the plates 13 be moved on lines intermediate of these two positions in order to secure a proper meshing of the gear elements, as will be readily comprehended.

V-shaped plates 16 have their inner arms overlapping and pivotally connected to the end portions of the bridge-tree 3 and have their outer arms formed with slots 17, through which bolts pass to adjustably connect them with the longitudinal beams of the base. The upper ends of the stub-axles 14 pass through openings in the axle ends of the V-shaped plates and receive pins 18, by means of which said plates are prevented from vertical displacement.

When the master-wheel 5 is set in motion, it causes the gear-wheels 12 to correspondingly turn upon the stub-axles 14 and transmit motion to the pinions 11, and from thence to the line of shafting 6, through the instrumentality of the intervening gearing, as herein described, and illustrated in the accompanying drawings.

The vertical shafts 9 when properly positioned are not subjected to side stress, inasmuch as the pairs of gear-wheels 12 exert an equal pressure against the opposite side of the pinions 11. Hence the gearing will wear uniformly and the horse-power be more durable and lasting than if the gear-wheels 12 were dispensed with and the pinions 11 caused to mesh directly with the cog-teeth of the master-wheel 5, as commonly practiced.

Having thus described the invention, what is claimed as new, and desired to be secured by Letters Patent, is—

1. In a horse-power, substantially such as described, the combination with a suitable base, a master-wheel journaled thereon and a line-shaft, of a vertical shaft supported on the base independently of the master-wheel and geared to the line-shaft, bearing-plates fixed to the base on opposite sides of the vertical shaft, and a pair of transmitting-pinions journaled on the bearing-plates independently of the master-wheel and disposed on opposite sides of the vertical shaft, said pin-

ions intermeshing directly with the master-wheel and the vertical shaft, whereby the pair of pinions equalize the strain of the master-wheel on the vertical shaft and maintain the axes of the shaft and master-wheel in parallel relation. 70

2. In a horse-power, substantially such as described, the combination with a suitable bed, a master-wheel, and a line-shaft, of a vertical shaft supported on the bed independently of the master-wheel and geared to the line-shaft, and a pair of transmitting-gears disposed on opposite sides of the vertical shaft, supported independently of the master-wheel, and intermeshing directly with said wheel and the vertical shaft to equalize the strain on the latter, each transmitting-gear being adjustable in an oblique path between the toothed faces of the master-wheel and the shaft, whereby the transmitting-gear may be moved to mesh uniformly with the wheel and shaft-pinion, as set forth. 80

3. In a horse-power, substantially such as described, the combination with a suitable bed, an internally-toothed master-wheel, and a line-shaft, of a vertical shaft journaled on the bed within the master-wheel, independently thereof, and geared to the line-shaft and provided with a spur-pinion, bearing-plates 90 provided with stub-axles and adjustably fastened on the bed on opposite sides of the vertical shaft, and transmitting-gears mounted on said stub-axles to intermesh directly with the master-wheel and with the shaft-pinion, 95 each transmitting-gear being adjustable with its bearing-plate in an oblique direction for uniformly meshing with both the master-wheel and shaft-pinion as set forth. 100

4. In a horse-power, substantially as described, the combination with a suitable bed, an internally-toothed master-wheel, and a line-shaft, of vertical shafts supported on the bed at diametrically opposite points within the master-wheel, geared to the line-shaft in 110 different points along its length, and having gear-pinions at the upper ends, and pairs of transmitting-wheels in mesh directly with the master-wheel and with the gear-pinions of said vertical shafts, each pair of transmitting-wheels being supported on the bed on opposite sides of the shaft-pinion to equalize the strain on the shaft and each transmitting-pinion being adjustable in an oblique path to secure uniformity in the intermeshing of its 115 teeth with said master-wheel and the shaft-pinion, substantially as described. 120

5. In a horse-power, the combination of a bed having a cross-tree, an internally-toothed master-wheel, a line-shaft, the vertical shafts 125 supported in the bed at diametrically opposite points of the master-wheel and geared to the line-shaft, the slotted plates fastened adjustably to the bed on opposite sides of the vertical shafts and provided with the stub-axles, the brace-plates each connected loosely 130 with the stub-axle of one plate, attached at

one end to the cross-tree, and fastened adjustably at its other end to the base, and pairs of transmitting-gears journaled on the stub-
axles on opposite sides of the vertical shafts
5 and meshing directly with the master-wheel
and with the vertical shafts to equalize the
strain on the latter, substantially as described.

In testimony that I claim the foregoing as
my own I have hereto affixed my signature in
the presence of two witnesses.

GEORGE D. WILSON.
